UNITED STATES PATENT OFFICE.

JAMES H. MORLEY, OF HOLYOKE, ASSIGNOR TO THE MORLEY SEWING MACHINE COMPANY, OF BOSTON, MASSACHUSETTS.

HEAVY-FABRIC SEWING-MACHINE.

SPECIFICATION forming part of Letters Patent No. 270,971, dated January 23, 1883.

Application filed February 1, 1882. (No model.)

To all whom it may concern:

Be it known that I, JAMES H. MORLEY, a citizen of the United States, residing at Holyoke, in the county of Hampden and State of Massachusetts, have invented new and useful Improvements in Heavy-Fabric Sewing-Machines, of which the following is a specification.

This invention relates to that class of sewing-machines known as "needle-feed" machines, and to the details of the construction of machines of that class to particularly adapt them to heavy-fabric lap and butt seam work, the object being to provide a machine for heavy-fabric sewing, in which the needle-feed motions are positive in both directions and easily adjustable to varying lengths of stitches, one having the operative parts reduced to the least practicable number, and requiring but little power to run it, and to provide special attachments therefor, whereby the machine is adapted to a great variety of heavy work.

In the drawings forming part of this specification, Figure 1 is a side elevation, partly in section, of a sewing-machine constructed according to my invention with the feller thereon. Fig. 2 is a vertical section on the line xx , Fig. 1. Fig. 3 is a plan view of the eyed needle bar. Fig. 4 is a plan view of the hook needle bar, together with the cast-off bar and its adjusting attachments thereto connected. Fig. 5 is a general perspective view of the operative parts of the machine with the frame thereof removed and the front plate thereof shown in dotted outlines. Fig. 6 is a view of the presser-foot and a part of the presser-foot bar, and illustrating the manner of passing a line of binding through said presser-foot and the tension device to operate upon said binding. Fig. 7 is a view, looking from the rear, of some of the operative parts of the machine, the swinging frame being removed. Fig. 8 is a side elevation, showing the ordinary arm of the machine removed and a tube sewing-arm substituted therefor. Fig. 9 illustrates a feller and gage adapted to be used with this machine. Fig. 10 is a rear end view of said feller and gage, showing the fabric as being folded therein in section. Fig. 11 illustrates the upper side, and Fig. 12 the under side, of the seam sewed by employing the feller and gage, Figs. 9 and

10. Fig. 13 illustrates a seam-gage adapted for use with this machine; and Figs. 14 and 15 are other views of the same seamer, showing the different methods of forming seams by the use thereof. Figs. 16 and 17 illustrate the opposite sides of fabric after having been sewed by the use of the seamer, Fig. 13. Fig. 18 illustrates the presser-foot of the machine, having attached thereto a butt-seam guide, together with sections of carpet fabric in place thereunder, as when the edges are being sewed together. Fig. 19 is a view of said butt-seam guide removed from the presser-foot. Fig. 20 is a view of the end of the tube-sewing arm, having thereon the tube-seamer, and showing the end of a band of fabric folded around said tube-seamer in a position to be sewed, a folding-ring encircling said band. Fig. 21 illustrates a section of fabric-tube folded and sewed. Fig. 22 is a view of the cloth-plate.

In the drawings, A is the frame of the machine. B is the oscillating frame. c is the shaft. d is a driving and cam pulley combined. e is the eyed needle bar. i is the hook-needle bar. o is the cast-off bar. r is the cast-off adjusting-stop. s is the cast-off bar-guide. v is the cast-off. x is the eyed needle. x' is the hook-needle. z z' are cranks on shaft c. a is the take-up cam. b is the presser-foot cam. b' is a grooved cam cut in the driving-pulley d. f is an elbow-lever. w is a connecting-rod. e' is the elbow-lever fulcrum-block. h is the presser-foot bar. n is the presser-foot. o' is the take-up. E is the front plate. i' is the presser-bar lever. K is the cloth-plate. v' is the presser-bar lever-stud. c' is the binding-tension on the presser-foot. c'' is the binding. a' are the oscillating-frame trunnions. a'' are the trunnion-bearings. n' indicates the cam-slots in the needle-bars. o'' is a cast-off bar friction-spring. o''' are studs on the front plate, E. m is the presser-bar spring. m' is a lever-block on the presser-bar. H is the cloth-plate stand on the arm J. o'' is the thread-tension. J is the arm of the machine. L is the tube-work arm. 5 and 5½ are respectively a feller and its gage. 6 indicates the fabric in Figs. 10, 11, 12, 14, 15, 16, 17. 7 is a seamer. 8 is a butt-seam guide. 9 is carpet fabric. 10 is a tube-seamer. 11 are tube-seamer guides. 12 is a tube-seamer folding-ring. 13 is tube-

fabric. 14 is tube-fabric sewed together. 15 is a binder-tension.

Like letters refer to like parts in the several figures.

5 The machine herein described is so constructed that the operator sits or stands at the rear end thereof, or at the extreme right in Fig. 1, and guides the edges of two pieces of fabric to a proper position between the upward-pressing presser-foot *n* and the cloth-plate *K*, where the needles pierce them and feed them along after each stitch from right to left, or from the rear toward the front end of the machine, as will be hereinafter fully set forth.

15 In this machine all the operative parts thereof are few in number, and are concentrated in that portion thereof directly under the cloth-plate stand on the end of the arm *J*.

The frame *A* of the machine is of an oblong form, running back from the front plate, *E*, and having its rear end of half-round form, upon which the arm *J* is properly secured. The general form of its front end is shown in Fig. 2. The said front end of the frame *A* is provided with two hollow trunnion-bearings, *a*³, set opposite each other and screwed into said frame.

A front plate, *E*, having on its inner face, studs *o*⁵, which are pierced vertically to receive the presser-bar *h*, a stud, *v*², to which is hung the presser-bar lever *i*², and a fulcrum-block, *e*², to which adjustably therein is pivoted the elbow-lever *f*, is properly secured to the front end of the frame *A*.

35 An oscillating frame, *B*, is constructed consisting of a base, 15, having two upright ends, 16, with inclined outer faces, two vertical posts, 17, standing upon said base, and having also inclined outer faces to correspond with those above named on said base, and a cross-tie, 18, uniting the upper ends of said posts 17. The said inclined faces of the upright parts 16 of said frame *B* and of said posts 17 are fitted to receive upon each end of the said frame two inclined needle-bars, *e* and *i*, which are suitably secured thereto to permit them to have an easy reciprocating motion on frame *B* in the direction of their length. Said needle-bars have each of them a cam-slot, *n*³, formed therein, through which the cranks *z* *z'* project; but the form of said cam-slots differs in each needle-bar, so that their motions upon frame *B* shall be differential. The needle-bar *e* has secured to its upper end the eyed needle *x*, and is actuated by the crank *z'*, while the bar *i* has the hook-needle *x'* secured to it, and is actuated by the crank *z*. Said needle-bar *i* is adapted to operate in a direct manner the cast-off *v*, which is tubular, and through which the hook-needle *x'* passes, as seen in Fig. 4. Said cast-off is secured to the upper end of the cast-off bar *o*, which is fitted onto frame *B* by the side of said needle-bar *i*, the latter being formed to receive it. A spring, *o*², is placed between

65 the outer edge of said bar *o* and its side bearing in frame *B* to crowd said bar and create sufficient friction to cause the cast-off bar to

rest stationary except when moved up or down by the needle-bar *i*. A cast-off adjusting-stop, *r*, is secured to the face of needle-bar *i* by a screw passing through a slot therein, as shown, said stop having an inclined edge, which stands under the lower end of the cast-off bar *o*, whereby the working-distance of the cast-off *v* from the point of the needle *x'* is determined by moving stop *r* to the right or left, so that when the needle-bar moves up to carry said needle through the fabric the lower end of the cast-off bar may be struck by such a part of said inclined edge as will carry the cast-off up to the proper height. A cast-off-bar guide, *s*, having a longitudinal slot therein, is secured to the face of the needle-bar *i* below the cast-off bar *o*, and a pin passes through, said slot into said bar *o*. Said guide *s* serves to draw the cast-off bar and cast-off down at a proper time after the thread-loop has been cast off from the hook-needle.

The above-described means of adjusting the upthrow of the cast-off *v* is demanded to adapt the relative working positions of cast-off and needle to fabrics of varying thickness. A shaft, *c*, is fitted to run in proper bearings in the vertical posts 17 in the oscillating frame *B*, and on each end of said shaft is secured a crank-block, in each of which is secured a crank, *z* and *z'*, which, as above described, projects through the cam-slots *n*³ in the needle-bars *e* and *i*. A hand-wheel, 21, for slowly turning shaft *c*, is secured to one of said cranks. Upon said shaft *c*, between said vertical posts 17 in frame *B*, is secured a grooved pulley, *d*, around which a proper band runs to give motion to said shaft. Thus pulley *d* is the driving-pulley, and has a cam-groove, *d*², cut in one side thereof, which receives the end of a roller-stud secured to the side (near its end) of the horizontal arm of the elbow-lever *f*, the latter being pivoted to the fulcrum-block *e*² on the front plate, *E*, as in Fig. 7. Said fulcrum-block is provided with several pivot-holes, and said elbow-lever is provided with coinciding holes, whereby the fulcrum-point of lever *f* may be changed by changing the position of the pivot-pin 22, and thereby such a change may be effected in the length of the movement of the upper end of the vertical arm of lever *f* as may be desired to produce a longer or shorter feed in the machine, as will be hereinafter more fully set forth. Said shaft *c* has fixed thereon, in addition to pulley *d*, the presser-foot cam *b* and the take-up cam *a*.

The oscillating frame *B* is provided with two trunnions, *a*², one located at each end of the base 15 thereon. Said trunnions fit into the ends of the hollow frame-bearings *a*³ in frame *A*, and said frame *B*, swinging in said bearings, has an oscillating motion, whereby its upper narrow end, together with the parts thereto attached, swings toward and from the end or front plate, *E*, shaft *c*, and the parts connected thereto moving with frame *B*. Said oscillating motion in frame *B* is produced by connecting the upper end of the vertical arm of the elbow-lever *f* with the upper part of the frame *B* by

the connecting-rod *w*. Thus, since the fulcrum-point of said lever *f* in block *e*² is immovable on plate *E*, and its horizontal arm is vibrated vertically by its engagement with the cam-groove *d*² in pulley *d*, vibratory movements of its vertical arm cause frame *B* to oscillate, as aforesaid.

It will be seen that the needles swing with frame *B*, and the extent of that swing to produce stitches of the desired length is determined by changing the fulcrum-point of lever *f*, as above described.

The presser-foot *n* is provided with two slots, as shown, through which the needles pass, and in which they swing in feeding, and is secured to the vertical presser-bar, which is supported in the studs *o*⁵ on the front plate, *E*. A block, *m*², is secured on said presser-bar, and a spring, *m*, is placed on the latter between said block and the lower stud, *o*⁵, whereby the presser bar and foot are forced upward. A presser-bar lever, *i*², is hung by the side of the stud *v*² on said front plate. One end of said lever, in which is a friction-roll, as shown, extends over cam *b* on shaft *c* and its opposite end bears upon the top side of said block *m*² on the presser-bar, so that once in each revolution of shaft *c*, and as often as a stitch is made by the needles, the presser-foot is depressed to free the fabric, so that it may be freely fed along by the needles.

The take-up *o*' is pivoted to frame *A* in the rear of the oscillating frame *B*, its vertical arm being provided with a suitable thread-guiding roll. One arm of said take-up reaches within frame *B*, and extends over the cam *a* on shaft *c*, whereby the requisite swing of said take-up to properly draw the thread is effected.

The arm *J* of the machine, attached, as aforesaid, to the rear end of the frame *A*, extends over to a point nearly over the center of the presser-foot, and to the end thereof is fixed the vertical cloth-plate stand *H*, whose lower end terminates in two feet, as shown in Fig. 2, to which is secured the cloth-plate *K*, having an opening therein to permit the needles to pass up through. For sewing ordinary butted or lapped seam work, which requires no binding, the machine is operated with the parts thereof constructed and arranged as above described; but when a heavy fabric is to be operated upon—such as that which enters into the fabrication of blankets and such similar goods—other and additional attachments are employed with the machine, as hereinafter described.

In sewing the aforesaid simple butted and lap seam work the machine is operated as follows: Connection by ordinary band with the driving-pulley *d* may be made with any convenient foot-power or other driving mechanism. Any convenient treadle attachment may be made with the lower end of the presser-foot shaft, whereby the presser-foot may be drawn down away from the cloth-plate for the purpose of inserting work therebetween, or for other purposes. If the parts to be united are to have a lap-seam sewed, one edge is laid upon the other between the presser-foot and the

cloth-plate, carrying their ends forward, so that the needles will pierce them when they first pass upward. The thread is passed around a tension-roller, *o*⁷, in the ordinary way, thence over a thread-roller, *90*, on frame *B*, (see Fig. 1,) thence back over a roller on the take-up, and thence through the eye of the needle *x*, a loose end being left, as usual. After the work has been properly placed in the machine, shaft *c* may be slowly turned by seizing the hand-wheel 21 to ascertain that all parts are properly adjusted to the work, when the machine may be started at full speed.

In sewing, the cranks *z* *z*', operating in the cam-slots in the needle-bars *e* *i*, carry said bars and their needles up and down. The eyed needle moves up and pierces the fabric, first carrying the thread considerably above the top of the fabric. The hook-needle follows and pierces the fabric, and the needles stand crossing each other; but the eyed needle having started down before the hook-needle cross it, a loop is formed on the side of the former, which the hook-needle passes up through and attaches itself to, and as the eyed needle draws down out of the fabric said loop becomes engaged with the hook-needle and is by it drawn down through the fabric, where, after the next loop is formed, it is cast off by the operation of the parts above described in the usual way. Previous to the time during the above-described sewing operation when both needles leave the fabric cam *b* and lever *i*² operate to press down the presser-foot, relieving the fabric from pressure, and then the cam-groove *d*² acts on the elbow-lever *f* to lift the end of its horizontal arm, and thus swing the upper end of frame *B* toward the front plate, *E*, which causes the needles to draw the fabric along or to feed it, when the needles draw quite down and swing back and repeat the above-described operations. The action of the take-up *o*', which is operated directly by the cam *a* on shaft *c*, is of the ordinary kind.

In sewing butted joints, with the parts of fabric arranged as is shown in Fig. 18, the operation of the sewing parts is the same as that just described, as also are they when other varieties of seams and felling are sewed—such as are shown in Figs. 16, 17, 11, 12, and 21; but when heavy work, like carpet fabrics *q* *q*, Fig. 18, is sewed a butt-seam guide, 8, is fixed on the presser-foot back of the rear edge of the cloth-plate, so that the edges of the fabric may be pressed together and held down to a proper position just before they encounter the needles.

As above alluded to, the operator on this machine stands at the rear end thereof and guides the work away from him toward the front of the machine, the arm *J* of the machine pointing from him and standing between his arms.

In sewing the before-mentioned heavy blanket-work, making what is termed the "back seam," (which, with its binding, is illustrated in Fig. 11,) the feller 5 and gage 5½ are used jointly, and the presser-foot, having the bind-

ing-perforation and the binding-tension c^2 , Fig. 6, is used. A presser-foot of the same construction is shown in Fig. 5. The seam illustrated in Fig. 12 may be sewed in the manner described last by drawing the binding away from the presser-foot. The binding c^2 is drawn from a roll under the machine, as in Fig. 1, being led up over a guide, where a tension-spring, 15, bears upon it, thence under a guide-roll, and thence up through the presser-foot n and under the binding-tension c^2 , of elastic metal, adjustable to press with greater or less force upon the binding, and thence over the face of the presser-foot to a position where the needles will penetrate it at the same time they do the fabric. It will be seen that as the fabric and binding are fed along together to be sewed the binding is kept straight and smooth by the action of tension c^2 upon it.

In arranging for sewing said back seam the feller 5 is secured to the presser-foot, as in Fig. 1, and the gage 5½ is secured to the cloth-plate. Said feller 5 is illustrated on an enlarged scale in Fig. 9, and is constructed with a flat plate-shaped base, 23, from which is folded, in a flat tubular tapering form, one edge of the plate to form an elliptic-shaped feller, with one edge of the plate 24 interposed between said base and the upper side of said feller. A slotted arm, 25, is attached to one side thereof, through which screws pass to secure the attachment to the presser-foot. The gage 5½ is bent, as shown, to correspond somewhat to the curve of the side of said feller. Fig. 10 illustrates, looking from the operator's standpoint, as above described, the rear end of said feller and guide and the positions of both edges of the blanket as it is being guided and fed therethrough preparatory to being sewed, as shown in Figs. 11 and 12. It will be observed that what is termed the "outside of the work" is carried next to the presser-foot.

Figs. 13, 14, and 15 illustrate a seaming attachment adapted to be used in making with this machine such seams as are illustrated in Figs. 16 and 17, which may be of a simple single-edge fold or a center seam, as shown in Fig. 17. In both of these cases the binding is used when the fabric is not of strong quality, to prevent the edges from pulling off. Said seamer, Fig. 13, consists of a base-plate, 26, having a turned-up side, 28, at right angles to the former, and of a cover-plate, 27, parallel to the face of plate 26, and connected to the latter by a vertical side, 29, whereby a fabric passage is formed between plates 26 and 27, and between the edge of the latter and said right-angled side 28, so that the edge of the fabric may be folded over the edge of said plate 27, the edge thereof lying between plates 26 and 27, as in Figs. 14 and 15. Said attachment is provided with the usual slotted arm, 30, whereby it may be secured to the presser-foot n , and is slightly raised above the latter by a block, 31, to permit, if desired, of passing the edge of a piece of fabric under

plate 26, so as to form a seam such as is illustrated in Fig. 17.

In adapting this machine to sew tubular work, as illustrated in Fig. 21, the tube-arm L is substituted for the arm J of the machine, and a cloth plate, K, is secured to the under side of the end thereof, as shown. A tube-seamer, 10, of cylindrical form, but having an edge attached to one side thereof and carried under the former and bent in the shape of an S, to form two seamer-guides, is attached to the end of said arm L, and a folding-ring, 12, encircles said cylindrical seamer, leaving room between the two for the fabric 13 to pass. Said fabric is in the form of a band, and being passed around the part 10 and within ring 12, with its edges inserted in the S-shaped guides 11, it is drawn out beyond the end of arm L, so that the needles may pierce it, when the latter will, as the machine is operated, continue to sew and draw the fabric along through said guide parts and deliver it in the form of a tube, as shown in Fig. 21.

The above-described sewing devices are peculiarly adapted to sew the strong, firm seams required in the manufacture of sails and like work.

I do not claim the various guiding and feeding devices other than that shown in Fig. 1, as the same may constitute subjects of separate applications; but I have shown and described the same to illustrate different operations with the machine set forth.

What I claim as my invention is—

1. In a needle-feed sewing-machine, an oscillating frame to carry two needle-bars at an angle to each other, and having trunnions thereon whereby it is pivoted to the machine, a driving-shaft hung in said oscillating frame, and appliances, substantially as described, for rotating said shaft and imparting an oscillating motion to said frame and shaft, all combined and operating substantially as set forth.

2. The combination, in a needle-feed sewing-machine, of an oscillating needle-bar frame, hung on trunnions in the frame of the machine, two needle-bars located on said oscillating frame at angles to each other, each having a cam-slot therein, a driving-shaft hung in said oscillating frame, and having cranks thereon to engage in said cam-slots in said needle-bars, and mechanism, substantially as described, for rotating said shaft and imparting an oscillating motion to said frame, needle-bars, and shaft, substantially as set forth.

3. The combination, in a needle-feed sewing-machine, of an oscillating needle-bar frame hung on trunnions in the frame of the machine, two needle-bars located on said oscillating frame at angles to each other, each having a cam-slot therein, a driving-shaft hung in said oscillating frame, and having cranks thereon to engage in said cam-slots in said needle-bars, appliances, substantially as described, for rotating said shaft and imparting an oscillating motion to said frame, needle-bars, and shafts, a presser-foot supported upon

a bar having supports in the frame of the machine, and means, substantially as described, whereby the said presser-foot is caused to have an intermittent vertical motion by the rotation of said driving-shaft, substantially as set forth.

4. In a needle-feed sewing-machine, an oscillating needle-bar frame hung upon trunnions in the frame of the machine, two needle-bars, each having a cam-slot therein, and each carrying a needle located on said oscillating frame at angles to each other, a driving-shaft hung in said oscillating frame, having two cranks thereon engaging in said cam-slots in said needle-bars, a take-up pivoted to the frame of the machine, and having an arm thereon extending over said driving-shaft, a cam fixed on said shaft to strike the arm of said take-up, and means, substantially as described, for rotating said driving-shaft and imparting an oscillating motion to said frame, needle-bars, and shaft, all combined and operating substantially as set forth.

5. In combination, the oscillating needle-bar frame hung on trunnions in the frame of the machine, a driving-shaft hung in said frame, a driving-pulley fixed on said shaft, and having a cam-groove formed in its side, an elbow-lever pivoted adjustably to a fixed stud on the machine, having its horizontal arm engaging with said cam-groove in said driving-pulley and its vertical arm connected to said oscillating frame, substantially as set forth.

35 6. In combination, the hook-needle bar *i*, the hook-needle *x'*, the cast-off bar *o*, cast-off *v*, and the stop *r*, having an inclined face and secured adjustably to the bar *i*, substantially as set forth.

40 7. In combination, the frame *B*, the needle-bars *e* and *i*, standing at an angle to each other and their needles, the cast-off bar *o*, and cast-off *v*, the adjusting-stop *r*, and the guide *s* on said needle-bar *i*, spring *o²*, and appliances,

substantially as described, for imparting a reciprocating motion to said needle-bars in the direction of their length, all as set forth.

8. The combination, with the sewing and feeding mechanism of a sewing-machine, of a presser-foot supported in the frame of the machine, and operated by mechanism, substantially as described, which is disconnected from the arm thereof, of a cloth-plate supported in a fixed position above said presser-foot, and of the feller 5, attached to said presser-foot, and the gage 5 $\frac{1}{2}$, secured to said cloth-plate, substantially as set forth.

9. The combination, in a needle-feed sewing-machine, of an oscillating needle-bar frame hung on trunnions in the frame of the machine, two needle-bars, with their needles located on said oscillating frame at angles to each other, each of said bars having a cam-slot therein, a driving-shaft hung in said oscillating frame, and having cranks thereon to engage in said cam-slots in said needle-bars, appliances, substantially as described, for rotating said shaft and for imparting an oscillating motion to said frame, needle-bars, and shaft, a presser-foot supported upon a bar having supports in the frame of the machine, and operating mechanism, and a cloth-plate supported in a fixed position above said presser-foot, substantially as set forth.

10. The within-described improved feller and gage 5 and 5 $\frac{1}{2}$, consisting of the flat base-plate 23, from which is folded in a flat, tubular, tapering form one edge of said plate to form an elliptic-shaped feller, with one edge, 24, of said plate interposed between said base-plate 23 and the upper side of said feller, and the curved gage 5 $\frac{1}{2}$, combined and operating substantially as set forth.

JAMES H. MORLEY.
